GAS BURNER

Robert A. Wittmann, Chicago, Ill., assignor to
Chicago By-Products Corporation, a corpora-
tion of Illinois

Application September 16, 1939, Serial No. 295,186

2 Claims. (Cl. 158—99)

My invention relates to gas burners. The present application is a continuation in part of my prior application Serial Number 142,358, filed May 13, 1937. The present burner is designed to secure a combination of actions which cooperate to produce efficient combustion over a wide range of rates of combustion and a freedom from flashback. The specific form herein shown and described is constructed from a length of seamless metal tubing which is an ideal medium because of thin walls of high heat conductivity and the facility of securing the desired shapes of the functional parts in a simple efficient manner. However, the method of construction is not herein claimed. The present invention is in the structure which secures a novel interrelation of actions and capabilities which give the burner superior operating characteristics and large capacity in small space.

The burner of my invention embodies certain structural features and relations as follows:

The gas (mixed with primary air) is supplied to relatively long narrow ports through a narrow passageway defined by parallel vertical walls. These walls are spaced apart a distance which is small enough to act as a flame arresting passageway when the walls are kept relatively cool. The parallel walls extend above a distributing duct far enough to be effectively cooled by free flow of secondary air around and in contact with them.

The ports are direct continuations of the narrow flame arresting passageway without any constriction, hence the velocity of gas flow is substantially the same in the passageway as out of the ports and a temporary down draft or back pressure which forces the flame down does not give the flame a chance to propagate in a region of lower velocity below the port.

The cross-sectional shape or external outline of the burner tube at the ported portion resembles somewhat an elongated truncated teardrop shape with the gas ports at the truncated end. The secondary air flows upwardly along the side walls, cooling them and arriving at the port and tending to pull the gas air mixture out of the slot-like port in a thin narrow sheetlike stream in ideal form for intimate mixture and consequent complete combustion. Now the completeness of combustion of a fuel gas with reference to the oxygen of the air depends upon repeated opportunities for a combustible gas particle to meet an oxygen particle of the air while these two gases are at ignition temperature. Turbulence is a means for creating these opportunities. It has been demonstrated in many instances that high

turbulence is very effective in securing completeness of combustion, under the conditions of maintained ignition temperature.

According to my present invention, I produce the turbulence by means of the eddies formed at the square stern of a body, the sides of which permit substantially streamline flow to the square stern. In the present invention, the square stern is the active face of a burner, that is the face containing the gas emitting port. As will appear from a later detailed description, the burner of my invention provides directing side walls which permit or induce streamline flow to occur along the sides of the burner to a square end or square stern relative to the direction of air flow. Air flows to the square stern on each lateral side, so that when the stream arrives at the square stern eddies are formed at the shoulders of the square stern. The wall thickness outside the gas port is so selected relative to port thickness and air velocity as to secure the benefit of this turbulent effect. The gas port between these shoulders, is so proportioned in width to the thickness of the shoulders and to the velocity of air flow that the air flow produces the desired turbulence and the issuing stream of gas is so thin that there is produced a very high ratio of area to volume of the issuing gas. As the result of these two actions, that is, the turbulence, and the inherent nearness of any gas particle to the surface of the issuing gas stream, the turbulence at the edges of the port sets up a thorough mixing of the issuing gas and the flowing air, with the result that the flame or field of combustion bugs the shoulders of the square stern, giving a very short flame, substantially colorless and effecting substantially perfect combustion of the gas. The flame is short because it does not need to reach for its oxygen.

The air flow along the sides of the burner is produced by the thermodynamic action of the heat of combustion which expands the air in the vicinity of and above the flame, and causes the air to rise and thereby creates the necessary upward flow to produce the action above described. The velocity of air flow is low but by suitably relating the above factors the desired effect is readily secured. The flow of the secondary air along the side walls which define the narrow passageway and slotted port between them tends to keep the side walls cool by carrying off heat therefrom.

The specific mechanical construction herein disclosed and constituting the preferred embodiment of the invention involves the use of a tube

or sheet of metal of desired thickness and of good heat conductivity which is formed to the desired shape. Numerous methods of forming or shaping as by slotting and bending, or by bending and slotting, or other operations, will at once occur to those skilled in the art, but specifically, there is an advantage in forming the tube out of a single piece of seamless tubing. The tube herein illustrated and described as the preferred form is mechanically organized into functional parts as follows: First, there is an injection mixer which restricts and proportions the air flow and gas flow. Second, there is a duct for conducting the gas and primary air along the length of the burner. Third, there is a slot or narrow passageway which serves to equalize the outflow along the length of the burner. Fourth, there are the ports opening onto the end faces of the side walls or stern of the burner, and, fifth, there are the integral bridges performing the mechanical function of holding the edges of the slot at the right spacing, and the fluid flow function of sealing off the air flow along the sections of the burner to equalize the outflow of gas of the corresponding section and to prevent uneven burning and backfiring.

While I have herein described a specific form of burner tube embodying the full complement of functions above recited, it is to be understood that the invention may be embodied in various forms in which some of these functional parts may be modified or omitted.

The burner, whether consisting of a single tube, or a plurality of tubes in parallel, has a low heat content. The metal does not get overheated. The burner itself runs cool and stays clean.

In operation, the burner lights easily and starts off promptly without any noise. It burns very quietly over a wide range of rates of combustion without flashback or lifting of the flame, and when the gas is shut off, the burner goes out without the slightest noise or puff.

The burner produces substantially perfect combustion over a wide range of gas pressures and flows, and operates with substantially uniform flame distribution over its entire ported surface. The flame will not lift or blow off the ports but instead hugs the ports closely and produces complete combustion of the gas almost as soon as it is issued. There is no formation of carbon or carbon monoxide, the burner being peculiarly clean and free of deposits or odors.

The ports are formed as narrow slots of a relatively great length compared with width. These ports are flanked with the square stern shoulders. Adjacent the shoulders are vertically extending lateral surfaces which permit streamline flow to the shoulders where turbulence is brought about. The gas ports are so proportioned that the gas flow issuing therethrough presents a very large ratio of lateral surface to volume. Not only is the ratio of lateral surface to volume large, but the transverse dimension, i. e., thickness of the stream, is so small that every gas particle is only a minute distance from the surface where it can get the necessary oxygen for combustion. With such small distance to travel laterally to secure contact with the air only a narrow depth of turbulence is needed to secure the desired completeness of combustion. Hence, although the secondary air velocity is low and does not have great energy content, by proportioning the thickness of the issuing gas stream, the width of the shoulders, velocity of the issuing gas and the primary air ratio all to the velocity

of the secondary air the desired effect of turbulent flame and complete combustion is obtained.

I am aware that it is old to make a flat flame burner of a single slot or a series of slots, but the action is wholly different from that of the present invention. In the fish tail burners the gas without secondary air is forced by pressure through the slot and produces a large sheet of luminous flame. According to the present invention the gas, mixed with primary air, passes out of the slot and is immediately involved in an eddy or turbulence which produces a very short squat non-luminous flame. In fact the flame is nearly invisible. Thorough mixing of the gas with the primary air before delivery of the mixture to the ports is a requirement of an ideal burner. In the present structure, the pull of the secondary air upon the burner ports during operation pulls air in through the venturi. The venturi, as above mentioned, restricts the inflow of air by its throat. The velocity of the gas and air through the throat produces the desired mixing of gas and the primary air in the interior of the burner tube.

In order to acquaint those skilled in the art with the manner of constructing and operating a device embodying my invention, I shall now describe, in connection with the accompanying drawings, a specific embodiment of the invention, and the manner of constructing and using the same.

In the drawings:

Figure 1 is a side elevation of a gas burner tube embodying my invention, shown in connection with its supporting and gas supplying means;

Figure 2 is a top plan view of the burner tube;

Figure 3 is an end view of the burner tube taken from the left of Figure 2, showing the Venturi-shaped inlet;

Figure 4 is a cross sectional view through the throat of the burner, taken on the line 4-4 of Figure 1;

Figure 5 is a vertical cross sectional view taken on the line 5-5 of Figure 1;

Figure 6 is an end view taken from the right of Figure 2;

Figure 7 is a diagrammatic illustration on a greatly enlarged scale of the action of fluid flow at the square stern of a solid body disposed in a fluid stream;

Figure 8 is a similar diagrammatic view of a solid body of a shape to produce substantially minimum disturbance in streamline flow in a stream of fluid;

Figure 9 is a similar diagrammatic view of a body similar to that of Figure 8, but having a square stern;

Figure 10 illustrates on an enlarged scale the action of gas and air flow past the square stern of the present burner;

Figure 11 is a fragmentary cross sectional view on an enlarged scale illustrating a modified form of square stern for the burner in which the face of the burner is concave;

Figure 12 is a cross sectional view illustrating the grouping of a series of burner tubes in parallel and illustrating the thermodynamic action of producing a vertical current of air which flows along the sides of the burner tubes; and

Figure 13 is an isometric view of a nozzle illustrating the function of the bridges in sealing the air flow acting upon a given port, indicating

the large area of gas flow exposed to the secondary air.

I shall first describe in detail a specific and preferred embodiment of the invention and then explain the method of combustion which it carries out and the principles upon which it operates.

The burner tube 1 shown in Figures 1 and 2 comprises a series of functional parts, first, the air and gas inlet portion 2, which comprises a Venturi-shaped throat forming part of an injector; a duct 3 for conducting the gas with primary air throughout the full length of the burner; a distributing slot 4 for equalizing the pressure along the gas outlets or ports 14-14 and the burner face 5 which provides the gas ports and square stern hereafter described in detail.

Preferably, the burner tube herein shown is constructed of a piece of seamless aluminum tubing, of suitable wall thickness, diameter and length, which is suitably slotted and die formed into the shape illustrated. Obviously, the tube need not be a seamless tube. It could be a seamed tube if so desired, or the burner could be shaped out of one or more sections of sheet metal if so desired. However, there is a simplicity and directness in forming the tube out of a piece of tubing of uniform initial diameter. In forming this tube, shown in Figures 1 and 2, the original tubing is die shaped to produce the configuration illustrated and described. A part of the walls of the tube are collapsed along the sides of the Venturi portion to produce the fins or webs 6, 6 which are of gusset shape, the object being to reduce progressively the diameter of the tubular portion to a throat 7 at the narrowest part and to form gradually expanding tubular portion 8 which merges into the tubular duct 3 and into the flattened slot defining portion 4. The walls of the slot defining portion 4 are approximately parallel at the top of the burner as illustrated in Figure 1, that is, as they reach the burner face 5 which forms the square stern portion. These side wall portions which approach parallelism as illustrated at 10, 10 in Figures 5 and 10, terminate in square edges 12, 12 where the metal of the original tube wall has been removed or cut away. This removal may be effected by punching or slotting the walls of the tube prior to forming or it may be done by cutting or grinding away the metal after the tube is formed in the dies, or it may be done in any other preferred manner.

The edges 12, 12 of the side walls 10, 10 provide the square stern to streamline flow, as will be described later. A series of integral bridges 13, 13 which are continuations of the side walls when the side walls are folded together, form a series of ties and seals for the ports 14, 14 which lie between them, and which are, in effect, continuations of the slot between the walls 10, 10, which slot terminates on the face of the square stern portion 5 in the ports 14, 14. The rear end of the burner tube is closed as by collapsing the walls by pressure, as shown at 15, 15. The rear end, which is in the shape of a vertical fin, may rest in a notched support 16 forming part of a supporting frame. The front end of the tube is provided with a bracket 17 which has a tubular portion 18 adapted to receive a gas nozzle 19 which nozzle is carried by a manifold 20. Gas is admitted to the manifold 20 through a suitable valve under control of the operator or attendant. The bracket 17 is C-

shaped and is formed of two like sheet metal parts welded together, there being wings 21, 21 which grip the adjacent portions of the webs 6, 6 between them, whereby the C-shaped bracket is rigidly connected to the burner tube. The gas nozzle 19 has a suitable bore or opening for discharging a stream of gas into the throat 7 through the funnel shaped inlet portion 8. This introduces a proportionate volume of air into the inside of the burner tube. The flow of gas and primary air expands and decreases in velocity through the expanding portion 9 and is conveyed to the duct portion 3. Gas mixed with primary air flows throughout the length of the duct 3 to the narrow slot in the portion 4 between the side walls 10, 10, and issues at the ports 14, 14 between the bridges 13, 13. The gas may be ignited at one end of the row of ports and it will quickly be transmitted the full length of the tube. The ports 14, 14 are separated by the bridges 13, 13, which bridges perform the dual function, first of mechanical support for the edges of the walls 10, 10, and, second, of sealing the burner portions with air, so that the effect of the air flow is equalized on the respective ports, particularly if there is a component of air flow endwise of the tube. The wall thickness and width of the shoulders 12, 12 and the width of the port 14 may for example be approximately $\frac{3}{64}$ " each.

In operation, the burner produces a very low (i. e., short) intense flame which is almost invisible, but of very high efficiency of combustion, that is, completeness of combustion. The thin gas stream and the turbulence produced at the issuing point of the stream result in rapid and complete combustion. The flame does not need to reach for oxygen as the oxygen is churned into it immediately. Combustion in this burner produces substantially no detectable carbon monoxide. The flame is very low and squat, and has a peculiar fuzzy appearance which is produced by the turbulent burning.

I shall now explain the manner in which turbulent combustion is produced in this burner.

Assume, as shown diagrammatically in Figure 7, that a solid body 25, with a square stern 26, is disposed in a stream of fluid flow and that the fluid assumes a streamline flow along the sides of the body, the streamline flow will be broken when the fluid passes the square stern, resulting in a region 27 of generally reduced pressure and of violent turbulence caused by the fluid attempting to fill the space and in doing so resolving itself into eddies. Depending upon the relative velocity between the body and the fluid stream and the density of the fluid stream, the size of the area 27, the reduction in pressure and the violence of disturbance therein will vary.

It is known that in order to reduce the disturbance of a solid body passing through a fluid, or of a fluid flow past a solid body, the shape which offers minimum opposition to such flow is like that of a falling raindrop or what might be called a tear drop shape in cross section. Such a shape is illustrated in Figure 8. It will not produce eddies at the rear or stern. Obviously the proportions will be varied for the relative speed between the fluid and the solid and for the density of the fluid, but the general character of the shape is well known.

If, now, the stern portion of the teardrop or tadpole shape shown in Figure 8 be cut off, as

illustrated in Figure 9, to produce a square stern 29, the region of turbulence 27 will attempt to fill out the shape of the ideal form with an eddying mass of the fluid.

If, now, the solid body 28 be hollowed out according to the dotted line 30, it will be seen that an approximation of the present burner nozzle is thereby produced. The suction which tends to form in the region 27 will tend to assist the outflow of any gas within the hollow interior of the body. In either event this region 27 will be in disturbance if the ratio of velocities, stream thickness and shoulder width be coordinated.

Now in the operation of the present burner, the gas is first turned on and flows through the pipe 20 and nozzle 9 into the Venturi portion 6 by way of the funnel-shaped opening 8, the neck 7, expanding tube 9, to the interior of the duct portion 3 and the slot portion 4. Referring now to Figure 10, gas issuing through the relatively narrow passageway of the slot portion 4 and issuing out of the port 14 tends, of itself, to issue as a sheet like the old fishtail burner, although, due to the design of the present burner, the velocity of issuance is relatively low since the pressure of the fuel gas itself is not applied to the ports but only through induction by the effect of the nozzle 19 and the Venturi portion 6. As soon as the gas is ignited the air is expanded by the heat of combustion and induces a fluid flow vertically, as will be apparent from the diagram of Figure 12 where a series of burner tubes 1, 1 are placed side by side. The region of hot expanded air above the burner in conjunction with the region of colder and denser air below the burner tube induces a vertical draft producing an effective vertical streamline flow of the air around each one of the tubes vertically as illustrated diagrammatically in Figure 9. This vertical flow of secondary air immediately produces the region of turbulence at 27, with the result that the flame, instead of being a flame of the fishtail type, is a low, squat, fuzzy looking flame, which is little more than a blue haze producing a combustion more complete than any other burner known to me. During combustion at the ports 14 the reduced pressure created in the region 27 (Figure 10) by the flow of secondary air pulls the gas-air mixture out of the ports 14.

The essential features for securing this result are the thin sheet like issuing stream of gas and the turbulence so related to it as to secure almost instant churning together of gas and air. When greater turbulence can be sustained by reason of greater air velocity and hence greater energy content the thickness of the stream of gas may be greater. Those skilled in the art will readily be able to correlate these two basic features.

The interruption to streamline flow at the face of the burner tends to cause in the region 27 a reduction in fluid pressure which the eddies tend to fill in. The reduction in pressure is not intended to be the sole control of the flow of fuel gas which arrives under sufficient pressure to produce outflow independently of the reduction of pressure. However, the reduction in pressure in conjunction with the expansion of gas when burning tends to produce an equalization of flame along the length of the burner port. This is a highly useful effect. The burner tends to keep a surprisingly uniform flame along its length for any given rate of gas feed.

Tests of the products of combustion indicate 75

a substantially perfect, that is, complete union, of the combustible particles with air, with the result that there is no carbon monoxide detectable and there is no deposit of carbon or gums on the burner. Since the flame is low and squat, and produces no substantial luminosity, the height of the flame, even when a high rate of combustion is proceeding, is very short and squat and does not lift off of the shoulders 12, 12 but remains close to them. Any heat which is transmitted from the burning gases to the metal of the shoulders 12, 12 is rapidly dissipated by contact with the thin walls of the stream of secondary air which hugs the surfaces of these walls. Hence, the burner tube, which preferably is of aluminum, although obviously it may be made of other metals or alloys, always remains cool and no part of the burner tube becomes overheated. The heat which is conducted through the metal and is transferred to the secondary air further assists in the completeness of combustion.

While I speak of a square stern portion as forming the face of the burner, it is to be understood that this is a functional designation rather than a definition, in that obviously the surfaces 12, 12, do not need to lie in the same plane, nor do they need to be parallel. For example, in Figure 11 I have shown the edges 12', 12' of the sheet metal sides 10, 10 as being inclined inwardly and towards each other to produce a concave face. This may be more pronounced than shown in Figure 11. The important considerations are that the streamlined flow of fluids follow along the sidewalls 10-10 and then be interrupted or interfered with sufficiently to produce a region of high turbulence and that the issuing stream of fuel gas be so thin that the turbulence so produced is able to penetrate the full thickness of the issuing stream and produce a complete churning of gas and air immediately. If the turbulence is small the thickness of the gas stream must likewise be small. If the turbulence is more extensive a greater thickness of the issuing gas stream is permissible. Since any desired volume of flow may be attained for a given thickness of gas flow by merely extending the length of the ports or the number of tubes this requirement offers no practical limitation. The shoulders 12, 12 of the respective ports 14, 14 lie in substantially a straight line in the specific form shown. This is desirable where a planar zone of combustion is desired, but it will be apparent that the invention is not necessarily limited to that specific detail. By having the ports all at the same height, substantially equal effect is produced upon the respective ports. Instead of being a straight tube, obviously the burner tube might be coiled up into a coil, or disposed on a curve or otherwise the form thereof may be modified without departing from the invention.

The bridges 13, 13 which constitute the unslotted parts of the original tube wall serve the desirable function, mechanically, of spacing the side walls 10, 10 so as to maintain the sides of the slots 14 accurately for any variations in temperature or the like. They perform, also, an important function in tending to equalize the effect upon a port, or upon adjacent ports, as is illustrated diagrammatically in Figure 13. Assume a nozzle 35 made up of a section of the tube shown in Figures 1 and 2, with the ends thereof sealed except for the opening 36, and assume that adjacent layers or sheets of vertically flowing air 37,

37 flow vertically up along the sides of the hollow body 35 and past the shoulders 12, 12 on each side of the slots 14. It can be seen that these bridges 13, 13, in effect, tend to fill out the ends of the space in which the turbulence produced by combustion of the gas issuing from the port 14 occurs. Thus, in effect, the ends of the longitudinally extending region of turbulence 27 are sealed off because the sheet of air hugs the solid bridges 13 and tends thereby to produce a more uniform effect upon the specific port 14. Since each port is thus sealed by the fluid flow of the secondary air and the bridges 13, the likelihood of air being drawn down one port 14 in order to make up the complement of gas issuing at another port 14, is greatly reduced. Hence, the width of the port 14 is not so critical. It may be wider or narrower than the accepted figure of .08" for a tubular duct which will not tend to flash back. The present burner will function satisfactorily with a port width of .055" to as low as .040" without danger of clogging up and with no flash back.

It is, however, essential that the cross sectional outline of the burner tube at the ports be such as to permit the secondary air to flow around the outside walls of the duct 3 and hug the sidewalls 10-10 for the dual purpose of keeping the sidewalls 10-10 cool to serve as a flame arrester and to create the region of turbulence and reduction of pressure at 27, as above explained. To fulfill these requirements, the duct 3 is preferably round and the vertical walls 10-10 must extend far enough above the duct 3 that the rising stream of secondary air sweeps along their sides in flowing up to shoulders 12-12 where the ports are located. To do this effectively, the walls 10-10 should extend above the duct 3 by a vertical distance not less than the horizontal radius of the duct 3. Thereby the secondary will freely flow up from below around the duct and along the sidewalls 10-10.

I am aware that burners with a large number of round port openings closely disposed along the length of a burner tube are old; also that burners with a series of elongated openings are old, and I do not claim such as my invention. No device of the prior art of which I am aware has provided for the issuance of the gas from a narrow slot which may be of any desired length, wherewith means are provided on each side of the slot to produce eddies of secondary air by the flow of secondary air which at the same time keeps the walls defining the slot relatively cool. The width of the slot is so related to the eddy producing means that the gas issuing from said slot is immediately involved in a churning operation by the effect of the eddies with the result that a perfection of combustion heretofore unattainable is secured. The gas flame may be extended horizontally as long as desired by suitably extending the length of the slot, but the thick-

ness of the issuing stream must be no greater than what can be thoroughly churned by the size and energy of the eddies available.

In the light of the above, it will be apparent to those skilled in the art that the form and details of construction may be widely varied to meet particular conditions and that the novel principle and mode of burning may be embodied in a wide variety of forms.

I do not intend to be limited to the precise details shown except and unless the same are made a part of the invention defined by the appended claims.

I claim:

15 1. A burner tube of greater depth than width comprising a thin walled metal tube having a ported burner portion, said portion comprising substantially parallel vertical walls terminating in substantially parallel straight edges interrupted at relatively long intervals by relatively short integral upwardly arched portions of the side walls joining the side walls mechanically and holding them in spaced relation and having between said arched portions relatively long narrow port openings of the same width as the distance between said vertical walls, the lower parts of said vertical walls diverging outwardly and constituting integral walls of a tubular distributing duct which duct opens upwardly into said narrow passageway along its length, the cross sectional outline of the burner tube being approximately that of an elongated and truncated teardrop to permit upward flow of the secondary air to wipe the upper margins of said vertical sidewalls with substantially streamline flow, the said substantially vertical side walls extending above said duct portion a distance not substantially less than the horizontal radius of the said distributing duct and into the region where the upward current of secondary air induced by the burning of gas at said ports flows in effective heat exchanging contact with said side walls and cools the same, the narrow pasageway between said side walls comprising the only communication between the ports and said distributing duct, said narrow passageway between said cooled side walls being effective as a flame arrester to prevent flashback.

45 2. The burner tube of claim 1 characterized by 50 an integral induction portion forming a forward extension of the walls of the burner tube for the entry of gas and primary air, said induction portion comprising a double tapered Venturi portion the walls of which merge into triangular gusset shaped flanges of double wall thickness disposed vertically on opposite sides of the Venturi portion, the walls of each flange being integral at their outer margins.
